(57) **CLAIM**

The ornamental design for a driver housing, as shown and described.

DESCRIPTION

FIG. 1 is a perspective view showing embodiment 1 of a new design for a driver housing;

FIG. 2 is a front view of the driver housing of FIG. 1;

FIG. 3 is a rear view of the driver housing of FIG. 1;

FIG. 4 is a left-side view of the driver housing of FIG. 1;

FIG. 5 is a right-side view of the driver housing of FIG. 1;

FIG. 6 is a top view of the driver housing of FIG. 1;

FIG. 7 is a bottom view of the driver housing of FIG. 1;

FIG. 8 is a perspective view showing embodiment 2 of a new design for a driver housing;

FIG. 9 is a front view of the driver housing of FIG. 8;

FIG. 10 is a rear view of the driver housing of FIG. 8;

FIG. 11 is a left-side view of the driver housing of FIG. 8;

FIG. 12 is a right-side view of the driver housing of FIG. 8;

FIG. 13 is a top view of the driver housing of FIG. 8; and;

FIG. 14 is a bottom view of the driver housing of FIG. 8.

The driver housing in FIGS. 8-14 is shown with a break in the middle of the design. The broken lines between the symbolic break lines are understood to indicate unclaimed length and width.

All broken lines showing portions of the driver housing in all FIGS. are included for the purpose of illustrating environment and form no part of the claimed design.

1 Claim, 10 Drawing Sheets
